UNITED STATES PATENT OFFICE

147,247

DESIGN FOR A VERIFIER

George H. Kress, Johnson City, N. Y., assignor to
International Business Machines Corporation,
New York, N. Y., a corporation of New York

Application May 3, 1946, Serial No. 129,304

Term of patent 14 years

(Cl. D64—11)

To all whom it may concern:

Be it known that I, George H. Kress, a citizen of the United States of America and resident of Johnson City, Broome County, New York, have invented a new, original, and ornamental Design for a Verifier, of which the following is a specification, reference being had to the accompanying drawings, forming part thereof.

Fig. 1 is a front perspective view of a verifier, showing my new design.

Figs. 2 and 3 are side perspective views of opposite sides of the design; and

Fig. 4 is a rear elevational view, slightly in perspective.

I claim:

The ornamental design for a verifier, as shown.

GEORGE H. KRESS.
